UNITED STATES PATENT OFFICE.

CHARLS M. CARLSON, OF ODEBOLT, IOWA.

CORN-CULTIVATOR.

SPECIFICATION forming part of Letters Patent No. 700,017, dated May 13, 1902.

Application filed February 10, 1902. Serial No. 93,351. (No model.)

To all whom it may concern:

Be it known that I, CHARLS M. CARLSON, a citizen of the United States of America, residing at Odebolt, in the county of Sac and 5 State of Iowa, have invented certain new and useful Improvements in Corn-Cultivators, of which the following is a specification.

This invention relates to cultivators, and more particularly to that class known as 10 "straddle-row sulky-plows."

The object of this invention is to produce a plow in which the shovels may be automatically elevated for the purpose of disengaging weeds or other accumulations; further- 15 more, to provide a frame which is adjustable transversely, said frame having secured thereto the plow-beams.

Furthermore, the object of the invention is to produce a plow which shall possess advantages 20 in points of simplicity, efficiency, and inexpensive construction.

With the foregoing and other objects in view the invention consists in the detail of construction and in the arrangement and 25 combination of parts to be hereinafter more fully set forth and claimed.

In describing the invention in detail reference will be had to the accompanying drawings, forming part of this specification, where- 30 in like characters denote corresponding parts in both views, and in which—

Figure 1 is a plan view of a cultivator embodying the invention. Fig. 2 is a side view thereof.

35 In the drawings, 1 indicates an arched axle having ground-wheels 2. A rectangular frame 3 is secured to the axle and held rigid by the braces 4. A tongue 5 is secured to the axle and extends out over the frame 3, to which it is bolted. A doubletree 6 is pivoted to the tongue, has downturned ends to which the singletrees 7 are connected. An arched frame 8 extends over the tongue and has depending ends, to which the plow-beams 9 are pivoted. 40 A connection 10 from the doubletrees to each end of the arched frame acts as means for drawing the plow. The beams are provided with suitable shovels 11 and stirrups 12, the latter being engaged by the operator to guide 45 the shovels. A seat 13 is supported by the spring 14, extending across the frame. A lever 15 is pivoted to the bolt 15^a and to the

arched frame, said lever moving the arched frame from side to side, according to the movement desired in the plows. A guide 16 extends across the arch under the tongue, and a link 17 is pivoted to the guide and to the bolt 15^a, by which the lever 15 and the doubletree are connected to the tongue. A rack 18 is mounted on a support 19, which extends 55 between the sides of the rectangular frame, and supports 20 extend from the support 19 to the axle. A segmental rack 21 is secured to each support 20, and a lever 22 is pivoted to each segmental rack. Spring-pressed 60 pawls of any suitable construction are provided for the levers to hold them at varying adjustments on the segmental racks. The ends of the levers opposite the handles are connected to the plow-beams by means of the 65 chains 23 or their equivalents. Hence the said beams may be lifted and held elevated by the levers when the pawls engage the segmental racks.

Further means are provided for elevating 70 the shovels periodically at the will of the operator for discharging deposits of grass or weeds, said means comprising cranked levers 24, which are journaled in bearings 25, attached to the horizontal portion of the axle. 80 One extension of each of the crank-levers is connected by a chain or its equivalent to a shovel-beam, and the other extension of each lever is to be engaged by a tripping-cam 26, secured to the under surface of the felly of 85 the ground-wheel. The extensions lie nominally away from the wheel, where they are held by springs 27, but are projected into line where the cam will engage them by means of the levers 28, which are fulcrumed on the 90 hooks 29, secured to the rectangular frame. When there is an accumulation on the shovels, the handle ends of the levers are pulled inwardly and the opposite ends carry the extensions of the cranked levers into the paths 95 of travel of the cams, thereby causing the cranked lever to work and lift the beam and shovel, when the deposit will be discharged.

By the construction shown the draft is conveyed directly to the end of the beams, and the 100 said beams may be shifted transversely of the sulky by the manipulation of the lever 15. It is noted that all of said levers are within the reach of the driver's seat.

The construction, operation, and advantages will, it is thought, be understood from the foregoing description, it being noted that various changes may be resorted to in the proportions and details of construction for carrying the same into practice.

Having fully described the invention, what I claim as new, and desire to secure by Letters Patent, is—

10. 1. In a cultivator an arched axle, a frame rigid with the axle, a movable arched frame, means for adjusting it, beams having their ends connected to the arched frame, crank-levers mounted in the bearings, connections from the cranked levers to the beams, cam-tripping blocks on the wheels and means for projecting the crank-levers into contact with the tripping-blocks.
15. 2. In a cultivator, an arched axle, a frame rigid thereon, a movable frame having depending ends, segmental racks carried by the rigid frame, levers pivoted on the racks, connections from the levers to the beams, crank-

levers mounted in bearings on the axle, connections from the beams to the crank-levers, 25 springs encircling the crank-levers, tripping-blocks on the wheels and levers for projecting the crank-levers into the path of travel of the tripping-blocks.

3. In a cultivator, an arched axle, ground-wheels thereon, a frame rigid with the axle, a movable frame, a lever for adjusting the movable frame, plow-beams, connected to the movable frame, crank-levers suitably mounted, tripping-blocks on the wheels and means 35 whereby the crank-levers are moved into engagement with the tripping-blocks, as and for the purpose described.

In testimony whereof I affix my signature, in the presence of two witnesses, this 23d day 40 of January, 1902.

CHARLS M. CARLSON.
